RECLOSING DEVICE FOR CIRCUIT
BREAKERS

Lloyd W. Dyer, Swissvale, Pa., assignor to Westinghouse Electric & Manufacturing Company, East Pittsburgh, Pa., a corporation of Pennsylvania

Application November 3, 1934, Serial No. 751,378

5 Claims. (Cl. 200—33)

My invention relates, generally, to circuit controlling devices, and it has particular relation to reclosing mechanism for circuit breakers.

The object of my invention, generally stated, is to provide a reclosing mechanism for a circuit breaker, which shall be simple and efficient in operation, and which may be readily and economically manufactured and installed.

The principal object of my invention is to provide for automatically reclosing a circuit breaker when it is operated to the open position.

A more specific object of my invention is to provide for automatically reclosing a circuit breaker by means of a fluid switching device controlled by the operations of the breaker.

Another important object of my invention is to provide for successively reclosing a circuit breaker.

Still another object of my invention is to provide for successively reclosing a circuit breaker a predetermined number of times, and preventing further operation after the circuit breaker has been reclosed for the predetermined number of times.

25 Other objects of my invention will, in part, be obvious, and, in part, appear hereinafter.

My invention, accordingly, is disclosed in the embodiment hereof shown in the accompanying drawing, and comprises the features of construction, combination of elements, and arrangement of parts which will be exemplified in the construction hereinafter set forth, and the scope of the application of which will be indicated in the appended claims.

35 For a more complete understanding of the nature and scope of my invention, reference may be had to the following detailed description, taken in connection with the accompanying drawing, in which:

40 Figures 1 and 2 are views partly in section and partly in side elevation of a concrete embodiment of my invention, as located in the different positions in accordance with the movement of a circuit breaker; and,

45 Figs. 3 and 4 are views in side elevation of different positions of a circuit breaker to which this invention may be applied for controlling its operation.

In order to effect the reclosure of a circuit breaker, after it has been tripped to the open position, a container is provided which is arranged to be rotatable in accordance with the movement of the circuit breaker from the closed to the open position, and vice versa. In this embodiment of the invention the container is provided with two

compartments, one of which contains a quantity of liquid when the circuit breaker is in the closed position.

When the circuit breaker is tripped to the open position, the liquid flows through a restricted orifice into a cup which is located within the other compartment. When a predetermined amount of the liquid has been received in the cup, contact members are closed which complete an energizing circuit for the operating mechanism of the circuit breaker. The circuit breaker is then closed, and the liquid begins to flow back to its original position.

In the event that the circuit breaker is immediately tripped again, the foregoing cycle of 15 operation is repeated, and the circuit breaker is again closed. As long as the circuit breaker continues to be immediately tripped on reclosing, the reclosing mechanism will continue to effect its reclosure until substantially all of the liquid has 20 passed into the compartment which is in the lower position when the circuit breaker is in the open position.

It is then necessary to manually reclose the circuit breaker, and permit the liquid to flow back 25 to the compartment, which is in the lower position when the circuit breaker is in the closed position.

Referring now particularly to Figs. 1 and 2 of the drawing, the reference character 10 designates a liquid-tight container provided with an upper compartment 11, and a lower compartment 12, which are separated by means of a partition 13. The compartments 11 and 12 are, respectively, in the upper and lower positions when 30 the circuit breaker, to which it is attached, is in the open position.

As illustrated in Figs. 3 and 4 of the drawing, the container 10 is mounted for rotation on a bracket 14 which may be supported on a panel 40 15, on which a circuit breaker, shown generally at 16, may be mounted in the customary manner. The circuit breaker 16 comprises fixed and movable contact members 17 and 18, respectively, and an operating solenoid 19, which, on energization, is disposed to attract an armature 20 45 that is connected by means of links 21 and 22 to operate the movable contact member 18 into engagement with the fixed contact member 17.

As illustrated, the fixed and movable contact 50 members 17 and 18 may be connected to terminals 23 and 24, respectively, which, in turn, may be connected to the circuit which is controlled by the circuit breaker 16. Any suitable tripping mechanism (not shown) may be provided for trip- 55

ping the movable contact member 18, so that it will open the circuit. Such tripping mechanisms may include a series overload trip, or a shunt trip operated in response to a low voltage on the circuit or in response to any other characteristic of the load circuit, as is well known to those skilled in the art.

An additional link 25, provided with a rack 26, is connected to the pivot point between the links 21 and 22, as illustrated. The rack 26 is arranged to engage a gear wheel 27, which is secured to the container 10. When the circuit breaker is in the open position, the container 10 will assume the position illustrated in Fig. 3 of the drawing, and shown in detail in Fig. 1. When the circuit breaker is operated to the closed position, the rack 26 will effect the rotation of the container 10, so that it will assume the position illustrated in Fig. 4 of the drawing and shown in detail in Fig. 2. While the container 10 has been illustrated as being rotatable through an angle of 180°, it will be readily apparent that it may be arranged to rotate through a greater or lesser angle, depending upon the design and construction of the mechanism.

A liquid 28, which is preferably mercury, is located in the upper compartment 11, that normally is in the lower position when the circuit breaker is in the closed position. The liquid 28 is permitted to flow into the lower compartment 12 through an orifice 29. As illustrated, the rate of flow through the orifice 29 may be adjusted by means of a valve, shown generally at 30, which is provided with a hand wheel 31 for adjusting the discharge opening.

In the lower compartment 12, the liquid 28 flows into a cup 32 which is mounted on one end of a lever 33 that is pivoted at 34. A spring 35 is provided for balancing the weight of the cup 32, and the liquid 28 which flows into it.

When a predetermined amount of liquid 28 has been discharged into the cup 32, the biasing force of the spring 35 is overcome, thereby permitting a movable contact member 36, carried by the lever 33, to engage a fixed contact member 37. The movable and fixed contact members 36 and 37 are connected, respectively, as illustrated, to terminals 38 and 39, which are mounted in a cover plate 40 and insulated therefrom.

When the movable contact member 36 engages the fixed contact member 37, a circuit is completed from a current source, which is not shown but which is indicated, for effecting the energization of the solenoid 19. The armature 20 is then attracted and the circuit breaker 16 is operated to move the contact member 18 into engagement with the contact member 17 to complete the circuit.

As soon as the circuit breaker 16 is closed, the container 10 is actuated to the position illustrated in Figs. 2 and 4 of the drawing. The contact members 36 and 37 are then separated and the liquid 28, which had flowed into the cup 32, is discharged therefrom into the compartment 12 and begins to flow back through an orifice 41 into the compartment 11, which is now in the lower position.

It will be observed that the rate of flow of the liquid 28 back into the compartment 11 is restricted. If the circuit breaker 16 is immediately tripped out again, the foregoing cycle of operation will be repeated, permitting more of the liquid 28 to flow into the lower compartment 12.

This cycle of operation will be repeated until sufficient liquid 28 no longer remains in the com-

partment 11 to fill the cup 32 to such an extent that the biasing force of the spring 35 will be overcome. The reclosing mechanism is then automatically locked out and must be manually reset.

The mechanism may be manually reset by an operator manually operating the circuit breaker 16 by moving a handle 42 downwardly. As illustrated, the handle 42 is connected by means of a suitable linkage arrangement to the link 21, so that downward movement of the handle will cause the same movement of the circuit breaker 16 that is caused by the attraction of the armature 20 by the solenoid 19.

While the invention has been illustrated as being applicable to a circuit breaker of a type which is commonly known as a carbon circuit breaker, it will be readily apparent that it may be employed with other types of circuit breakers which may be closed by other operating means than a solenoid, such, for example, as a motor operated mechanism. Therefore, the illustration and description of this invention, in connection with a particular type of solenoid operated circuit breaker, is to be understood as being for illustrative purposes only.

Since certain further changes may be made in the above construction, and different embodiments of the invention may be made without departing from the scope thereof, it is intended that all matter contained in the above description or shown in the accompanying drawing, shall be interpreted as illustrative, and not in a limiting sense.

I claim as my invention:

1. An electric circuit controller comprising, an envelope having upper and lower chambers interconnected by a plurality of passages and movable from a normal position to another predetermined position, a quantity of fluid within the container normally located in the lower chamber when the envelope is in its normal position and which flows into the upper chamber through one of said passages when the envelope is moved to said other predetermined position and which flows back into the lower chamber through another of said passages at a restricted rate when the envelope is returned to normal position, a switch mechanism in the upper chamber adapted to be mechanically actuated by the weight of a predetermined amount of fluid flowing into said chamber through said first-mentioned passage, and means operable from without the envelope to adjust the rate of fluid flow into the switch containing chamber.

2. An electric circuit controller comprising an envelope having a switch chamber and a fluid storage chamber and movable between predetermined positions, said chambers being interconnected by fluid discharge orifices so constituted that fluid flows from the storage chamber into the switch chamber at a higher rate than from the switch chamber into the storage chamber in response to successive movements of the envelope between said predetermined positions, a quantity of fluid in the envelope, and a circuit controlling switch mounted in the switch chamber disposed to be mechanically actuated by the weight of a predetermined amount of fluid discharged therein from the storage chamber, whereby only a predetermined number of operations of the switch may be effected by successive movements of the envelope between said predetermined positions.

3. An electric circuit controller comprising a

- 5 container mounted for rotational movement about a horizontal axis and provided with a partition forming upper and lower compartments, a quantity of fluid in the container, a discharge orifice in the partition through which fluid in the upper compartment may flow into the lower compartment only at a restricted rate, a second discharge orifice in the partition through which fluid may flow from the lower compartment into the upper compartment only when the container is rotated through a half revolution, means for adjusting the rate of flow through said second orifice, and a mechanical circuit controlling switch mounted in the upper compartment disposed to be mechanically actuated in response to the flow of a predetermined amount of said fluid through said second discharge orifice.
- 10 4. An electric circuit controller comprising a container having an upper switch compartment and a lower fluid storage compartment, said container being rotatably mounted so that the upper compartment may be positioned below the lower compartment, a quantity of fluid in said container, a discharge orifice extending from the upper compartment into the lower compartment through which fluid may flow into the lower compartment only at a restricted rate, a second discharge orifice extending from the lower compartment into the upper compartment through which fluid may flow into the upper compartment only at a higher rate when the container is rotated to position the upper compartment below the lower compartment, and a switch mechanism having
- 15
- 20
- 25
- 30

contact members normally biased to the open position disposed in the upper switch compartment disposed to be actuated to close its contact members by the flow of a predetermined quantity of said fluid through said second discharge orifice.

5. An electric circuit controller comprising a container having an upper switch compartment and a lower fluid storage compartment, said container being rotatably mounted so that the upper compartment may be positioned below the lower compartment, a quantity of fluid in said container, a discharge orifice extending from the upper compartment into the lower compartment through which fluid may flow into the lower compartment only at a restricted rate, a second discharge orifice extending from the lower compartment into the upper compartment through which fluid may flow into the upper compartment only at a higher rate when the container is rotated to position the upper compartment below the lower compartment, a switch mechanism disposed in the upper compartment, and a cup member attached to the switch mechanism disposed to receive the fluid discharged by said second orifice to mechanically actuate the switch, whereby successive rotational movements of the container will effect a predetermined number of successive operations of the switch mechanism as determined by the total quantity of fluid and the relative discharge rates of the orifices.
